We claim the ornamental design for a basin for a wash system, as shown and described.

DESCRIPTION

FIG. 1 is a top perspective view of the claimed design;
FIG. 2 is a top view thereof;
FIG. 3 is a bottom view thereof;
FIG. 4 is a right side view thereof, the left side view is a mirror image of FIG. 4;
FIG. 5 is a back view thereof;
FIG. 6 is a front view thereof; and,
FIG. 7 is another right side view thereof.
The ornamental design which is claimed is shown in solid lines in the drawings.
The broken lines in the drawings are for purposes of illustrating portions of the basin for wash system that form no part of the claimed design. In FIG. 7 the additional broken lines included depict environmental structure that also forms no part of the claimed design.
